*Primary Examiner—Ruth McInroy**Attorney, Agent, or Firm—Joseph E. Gerber***[57]****CLAIM**

The ornamental design for a round-topped helmet cover, as shown.

DESCRIPTION

FIG. 1 is a perspective view of a round-topped helmet cover showing my new design;

FIG. 2 is a top plan view thereof;

FIG. 3 is a bottom plan view thereof;

FIG. 4 is a left side elevation view thereof, the right side thereof being a mirror image of the left side thereof; and, FIG. 5 is a front end elevation view thereof, the rear end thereof being a mirror image of the front end thereof.
